CARL ROBERT HUGO BONN, OF HILLHEAD, GLASGOW, SCOTLAND.

MACHINE FOR BENDING TUBES AND THE LIKE.

Application filed August 4, 1922. Serial No. 579,673.

To all whom it may concern:

Be it known that I, CARL ROBERT HUGO BONN, a subject of the King of Great Britain and Ireland and the Isle of Man, and a resident of 56 Gibson Street, Hillhead, Glasgow, Scotland, have invented new and useful Improvements in Machines for Bending Tubes and the like, of which the following is a specification.

- 10 This invention has reference to improvements in machines for bending tubes and the like and comprises the method of and means for bending tubes and the like such as rods which consists in gripping the tube adjacent 15 to the part which is to be bent in a clamp constrained to move in the path of the bend and in moving and guiding the tube endways so that it is fed round the bend as it is formed; the movement of the clamp being accomplished preferably by the moving tube or by gearing synchronizing with the mechanism for moving the tube or by both means. The tube in moving endways does not begin to bend till it has passed a guide 20 roller and when the tube is to be bent into a segment of a circle the axis of this roller is on or near a center line passing through the center of rotation of the clamp and at right angles to the endways moving tube.
- 25 To prevent the tube from being distorted a mandrel may be arranged within the tube and located at or a little beyond the guide roller. The distance of the clamp from its center of rotation would be varied as the 30 radius of the bend desired varies and in order that bends of different radii may be bent as desired the tube would be adjustable towards or from the center of rotation of the clamp either by its carrier being pivoted or 35 mounted upon suitable slides, or by mounting the axis about which the clamp swings in adjustable bearings. The machine may be used to bend rods by dispensing with the mandrel while the tube may be coiled into a 40 spiral or volute by suitable attachments hereinafter described.
- 45 In order that others skilled in the art to which this invention relates may properly understand the same I have hereunto appended four sheets of explanatory drawings in which:—

50 Figures 1 and 2 are respectively an elevation and a plan view of a machine con-

structed according to this invention for bending tubes. 55

Figs. 3, 4, 5, and 6 are transverse sections taken on the lines A. B. C. and D. of Fig. 2, respectively.

Fig. 7 is an elevation showing the tube, 60 being bent, in section.

Figs. 8, 9, 10, 11, and 12 are views similar to Fig. 7 but illustrate modified forms of mandrels to which reference will be made hereinafter more particularly.

Figs. 13, 14, 15, and 16 illustrate various 65 forms of clamps for the tube.

Each figure comprises a longitudinal sectional elevation and sections taken on the lines E. and F. respectively.

Figs. 17 and 18 each comprise a longitudinal sectional elevation and transverse sectional elevations on the lines E. and F. of a clamp for the tubes in which a mandrel is arranged. 70

Figs. 19 and 20 are elevation at right 75 angles to each other and Fig. 21 is a sectional view of a clamp for the tube for use when it is desired to bend a tube already bent.

Figs. 22, 23 and 24 are similar views of 80 a slightly modified form of clamp for the same purpose.

Figs. 25, 26 and 27 are diagrammatic views illustrating the operations of the machine; Figs. 25 and 26 being elevations at right 85 angles to each other and Fig. 27 being a plan view.

Figs. 28, 29, 30, and 31 are diagrammatic elevations illustrating slightly modified arrangements. 90

Fig. 32 is an elevation and Fig. 33 is a side view of an attachment for bending or coiling the tube into a spiral or volute.

Fig. 34 is an elevation and Fig. 35 is a plan view of a further attachment for assisting the arrangement illustrated by Figs. 32 and 33. 95

Referring to these drawings:—

In carrying this invention into effect or practice the tube bending machine in its preferred form consists of a sole plate 1, pivoted at its one end 2, and provided with a ram 3 arranged within a cylinder 4 which is provided with the usual connections for hydraulic or other pressure fluid. 100

The ram 3 is stationary and the cylinder 105

2

4 is adapted to slide thereon on suitable guides provided on the sole plate 1. The one side of the cylinder 4 is formed with a flat surface or face 5 against which the tube 14 to be bent rests and is clamped by means of a clamp 6. If desired this flat surface 5 may be provided with a V or other suitably shaped groove into which the tube 14 may be clamped. Preferably the clamp 6 consists of blocks 7 which may engage each other by means of shoulders or steps 8 and which are formed with V shaped or as shown curved faces adapted to contain the tube 14. A binding strap 9 provided with flanged ends 10 adapted to engage the interrupted projecting flanges 10 of the side 5 of the cylinder 4 embraces these blocks 7 which are secured together by means of a wedge or the like 11. The position of this clamp 6 may be adjusted 15 along the cylinder as desired to suit the tube which is to be bent.

At a suitable position adjacent to the sole plate 1 a vertical spindle or axis 12 is mounted in suitable bearings 13. The distance between this spindle 12 and the center of the tube would equal the radius of the bend which is to be given to the tube 14. This distance may be regulated by moving the sole plate 1 on its pivot 2 or by moving the sole plate (and therefore the cylinder 4 and the tube 14) in a parallel direction away from or towards the spindle 12 or if desired the sole plate 1 and its fittings may be stationary and the bearings of the spindle 12 may be adjustable to and from the sole plate 1.

When the sole plate 1 is pivoted, as illustrated, a sliding block 15 (Figs. 2 and 4) may be provided to hold same rigid after its position has been adjusted. This block 15 may be operated by a screwed rod 16. To slacken back the face 5 from the tube 14 after the operation of bending an eccentric 17 and sliding block 71 operated by a handle 18 45 may be arranged. A guide roller 19 adapted to bear against the tube 14 is arranged in such a position that the tube cannot bend till it has passed same. When the bend desired forms a segment of a circle this roller 19 50 would be arranged on a line (or approximately on a line) passing through the axis 12 and at right angles to the tube 14. Preferably and as illustrated by Figs. 1, 2 and 5 the roller 19 is carried by an arm or rod 20 55 mounted in a bracket 21 formed or provided on the sole plate 1. The distance of this roller 19 from the tube may be adjusted by a screw 22 so that the roller presses against the tube 1.

60 When tubes of a different size have to be bent this roller may be replaced by a larger or smaller one as desired.

The vertical spindle or axis 12 is provided at its upper end with a radial arm 23 having

a clamp 24 adapted to grip the tube 14 and whose position on the arm 23 may be adjusted by a screw 72 or other means. This clamp 24 as illustrated by Figs. 1, 2 and 6 preferably consists of two jaws or blocks 25 secured together by a wedge 26 and arranged between the limbs 27 of a bracket 28 so that they can neither turn in nor be pushed out of the bracket 28. This bracket 28 is mounted on a rod or pin 29, preferably having serrations or the like 30 so that it cannot rotate about its own axis. This rod or pin 29 is carried by the arm 23. Within the tube 14 a rod 31 is arranged which is secured at its one end 32 to the ram 3 (or the sole plate 1) and at its other end is provided with a head or mandrel 33 (Fig. 7). This mandrel or head 33 is preferably located a little in front of the roller 19.

The operation of this machine is as follows:—

At a suitable position adjacent to the cylinder 4 by means of the clamp 6 and lies against the surface 5. It is held firmly in that position by means of the clamp 6 and the roller 19. The end of the tube which is to be bent is held firmly by the clamp 24. The position of the machine and the tube 14 prior to the bending operation taking place is as shown by full lines in Fig. 2. Pressure fluid is admitted to the cylinder in the usual manner, for example, through the pipe or passage 34 in the ram 3 and moves the cylinder 4 endways on the sole plate 1. The cylinder 4 carries the clamp 6 and tube 14 with it. Since the clamp 24 can only move in a circle about the center of the spindle 12 the end of the tube 14 is carried round and the tube is bent into shape.

The mandrel 33 (Fig. 7) is for the purpose of assisting in the control of the bending operation and of preventing the tube 14 being distorted at the beginning of the bend and is preferably located a suitable distance in front of the center line of the roller 19 and axis 12. This center line is marked 35 on Figs. 7 to 12. The center of the mandrel 33 may be on the line 35 or it may be at any suitable distance from the line 35, for example, the position shown by Fig. 7 is about the preferred distance. Before the bending operation commences the rod 31 is centrally within the tube 14 and as the bending proceeds the mandrel falls from the center (due to the curvature of the bend) and as shown by Fig. 7.

Fig. 8 illustrates a form of mandrel similar to Fig. 7 but between the head 33 and a collar 36 a plurality of loose washers 37 are mounted on a square or like shaped portion of the rod 31. These washers 37 are provided with slots 38 so as to permit the movement of the rod 31. The washers near the head 33 have a diameter somewhat smaller

- than the diameter of the head 33 and those near the center line 35 the same diameter as the head 33. The washers support the tube 14 at the line 35.
- 5 Fig. 9 illustrates another form of mandrel which consists of two heads 39 and 40 one of them being on the line 35 and the other being at the preferred distance from the line 35. The rod 31 is pivoted to the head 40.
- 10 Fig. 10 is similar to Fig. 9 but the rod 31 is pivoted to the head 39. Fig. 11 is similar to Figs. 9 and 10 but the head 40 is connected to the head 39, which is of cylindrical shape, by a ball and socket joint 41. Further 15 heads may be fitted by ball and socket joints or the like as shown by dotted lines. In this case and in the arrangement illustrated by Fig. 10 the rod 31 remains centrally within the tube 14 while the head 40 swivels.

- 20 Fig. 12 illustrates a form of mandrel in which the head 40 is connected to the head 39 by a ball and socket joint 41 and both heads 39 and 40 are expandible. In this case the rod 31 is in the form of a sleeve fitted to 25 the head 39. The head 40 is split into two or more parts, preferably four parts, and pieces 73 are fitted into the head 39 so that when the rod 42 is pushed the split head and pieces 73 expand by reason of the wedge surfaces 30 44 and 43^a and press against the interior surface of the tube 14. If desired a rotating mandrel which may be fitted with rollers may be used instead of those described heretofore.

- 35 The spindle or axis 12 is preferably free moving but if desired it may be provided with gearing so that its motion synchronizes with the travel of the cylinder 4 and tube 14. The clamp 24 when the spindle 12 is free 40 moving, cannot rotate about its own axis but when the spindle 12 is geared it may swivel about its vertical center line. In order that the tube may not be distorted at the clamp 24 a block 45 is preferably located adjacent to 45 the clamp blocks or jaws 25.

- This block, as illustrated by Fig. 13, would be arranged on the inner side of the bend and would have a small clearance space 46 so as to support the tube 14; the bend commencing at the edge 47 of the clamp jaws 25. The inner surface of this block 45 would be rounded.

- 50 Fig. 14 illustrates a similar arrangement to that shown by Fig. 13 but the block 45 in this case is formed in one with the blocks 25 and extends right around the tube 14.

- Fig. 15 illustrates another form in which the blocks 45 are separate from the blocks 25 but there is no clearance space 46 and the 60 blocks 45 embrace the tube 14. Fig. 16 illustrates the block 45 formed in one with the blocks 25 and while there is no clearance space 46 there is a clearance space between the points 49 and 50.

- 65 In some cases, particularly when tubes of

comparatively large diameter are to be bent, a mandrel may be inserted into the end of the tube 14 in the clamp 24. As illustrated by Fig. 17 this mandrel may be of the expanding type and may consist of a plug 51 having a divided head 52 and slotted arms 53 which may be expanded by the conical head 54 and screwed rod 55. Fig. 18 illustrates a form of mandrel in the clamp 24 which does not expand and which consists of a plug 56 having a rod 57 and head 58. The rod 57 may be replaced by a chain or entirely omitted.

When it is desired to bend a tube which has already been bent, that is, to put a 80 double bend on the tube the forms of clamp illustrated by Figs. 19, 20 and 21 or Figs. 22, 23 and 24 may be used.

In these two modified forms of clamp the blocks or jaws 25 are provided with teeth 85 or serrations 59 which engage similar teeth on the limbs 27 of the bracket 28. The bent tube is placed between the blocks 25 which are adjusted to suit the bend and then these blocks are secured together by the wedge 26. 90

Figs. 25, 26 and 27 are diagrammatic views illustrating the operation of the machine. In Figs. 26 and 27 the position of the bent tube is shown by dotted lines. These views will be readily understood by the foregoing description of the operation of the machine. Fig. 28 is a diagram of a slightly modified form of machine.

In this case a fixed guide plate 60 takes the place of the surface of the cylinder against which the tube 14 is clamped and the tube is clamped to the cylinder as before or if desired the cylinder may be dispensed with and the tube 14 forced endways by 100 any other suitable means.

In Fig. 29 a roller 61 takes the place of the fixed guide 60.

In Fig. 30 a roller 62 is arranged so that it may swing about the axis 12 a given distance and as the cylinder 4 moves forwards this roller is carried around either by the cylinder, the friction of the tube, or similar means.

In Fig. 31 the face of the cylinder is replaced by roller 61 and the roller 62 moves around as before. The roller 62 will strengthen or reinforce the arm 23 during the beginning of the bend.

Instead of the face of the cylinder 4 being used to support the tube during the bending and help to control the bending action a plurality of pressure rollers may be substituted and the tube 14 would pass same by suitable means.

This machine may be used for bending tubes into spirals or volutes. As illustrated by Figs. 32 and 33 the spindle or axis 12 may be mounted horizontally instead of vertically and would be carried by a carriage 63 adapted to run on rails or guides 125 130

64. As the tube is bent into a circle the carriage would be travelled by suitable means so that the proper pitch is given to the coiled tube.

5 The sole plate 1 would be pivoted suitably at the bending end instead of at the other end 2 so that the tube 14 as it was moved forward would be in alignment with the angle of the coils. The diameter of the 10 coils would be regulated by adjusting vertically the position of the spindle 12.

If desired and as illustrated by Figures 34 and 35 rollers 66 and 67 may be arranged to guide the coils as they are formed. These 15 rollers would be mounted on a carriage 68 adapted to slide on an angled frame 69 so that their position vertically and horizontally would be regulated to suit the diameter of the coils. The spindle 12 is preferably 20 provided with a counter-balance weight 70 or the like.

The rollers referred to can also be provided with gearing enabling them to be moved out as the tube is fed past the guide 25 rollers and thus form a volute. In bending coils or volutes stops 73 operated automatically would be arranged so that as the tube was fed forwards intermittently by the clamp 6 advancing and retreating the tube 30 would be gripped and prevented from being drawn back by the clamp 6.

By dispensing with the mandrels rods may be bent as desired.

By reversing the operation of the 35 machine tubes already bent may be straightened.

I claim.

1. A tube bending machine comprising a supporting element; a cylinder and a ram 40 so mounted thereon as to provide relative movement therebetween; means for clamping a tube to be bent to said cylinder; a guide roller for said tube; an axis; an arm mounted on said axis; and a clamp-member carried by said arm adapted to engage 45 said tube, whereby the latter may be bent upon a movement of the same.

2. A tube bending machine comprising a pivoted sole plate; a cylinder and ram so 50 mounted thereon as to provide relative movement therebetween; said cylinder having a face portion extending longitudinally thereof; means for clamping a tube to be bent on said face; a guide roller disposed 55 on the side of said tube opposite to the said cylinder; and means for holding said pivoted sole plate rigid after its position has been adjusted.

3. A structure comprising a plate; a cylinder and ram carried thereby; means for 60 clamping a tube to be bent to said cylinder; a guide roller; an axis; an arm mounted on said axis; a rod carried by said arm; a clamp bracket so mounted on said rod as 65 to permit said bracket to move in a pre-

determined direction only; jaws carried by said clamp bracket; and means for securing said jaws together so as to clamp said tube.

4. A machine comprising means for moving endways a tube to be bent; an axis located at a distance from the longitudinal center line of said tube equal to the radius of the bend desired; an arm mounted on said axis; a tube clamp carried by said arm; a tube guide roller; a mandrel head located 70 approximately on a line passing through said axis and at right angles to said tube; and a second mandrel head located in advance of said first-mentioned mandrel head, 75 one of said mandrel heads having an integral neck portion secured to the other.

5. A machine comprising means adapted to move endways a tube to be bent; an axis located at a distance from the longitudinal center line of said tube equal to the radius 80 of the bend desired; an arm mounted on said axis; a tube clamp carried by said arm; a tube guide roller; and an expandible mandrel head located approximately on a line 85 passing through said axis and at right angles to said tube, said head comprising a plurality of movable parts and a wedging member therefor.

6. A machine comprising a plate; means mounted thereon and adapted to carry a 90 tube to be bent and to move the same endways; an axis located at a distance from the longitudinal center line of said tube equal to the radius of the bend desired; an arm mounted on said axis; a tube clamp 95 carried by said arm; a tube guide roller; an expandible mandrel head located approximately on a line passing through said axis and at right angles to said tube; a second expandible mandrel head located in advance 100 of said first-mentioned mandrel head, and an integral neck portion extending from one mandrel to the other.

7. A machine comprising a plate; means mounted thereon and adapted to carry a 110 tube to be bent and to move the same endways; an axis located at a distance from the longitudinal center line of said tube equal to the radius of the bend desired; an arm mounted on said axis; a tube clamp carried by said arm; a tube guide roller; an expandible mandrel head located approximately 115 on a line passing through said axis and at right angles to said tube; a second expandible mandrel head located in advance of said first-mentioned mandrel head; a ball-and-socket joint between said mandrel heads; members having wedge surfaces 120 located within said mandrel heads; and means for so operating said members as to expand said heads.

8. A machine comprising a plate; means mounted thereon and adapted to carry a tube to be bent and to move the same endways; an adjustable guide roller; an axis; 125

an arm mounted on said axis; a clamp bracket carried by said arm; a pair of jaws fitted to said bracket and adapted to grip said tube; members extending longitudinally from said jaws and around said tube; and bell-mouth or curved end parts at the extremities of said extending members.

9. A machine comprising a plate; means mounted thereon and adapted to carry a tube to be bent and to move the same endways; a guide roller; an axis; an arm mounted on said axis; a clamp bracket carried by said arm; a pair of jaws fitted to said bracket and adapted to grip said tube; members extending from said jaws longitudinally around said tube; and bell-mouth or curved end parts at the extremities of said extending members forming a clearance space between the gripping parts of said jaws or blocks and the said extending members.

10. A machine comprising a plate; means mounted thereon and adapted to carry a tube to be bent and to move the same endways; an adjustable guide roller; an axis; an arm mounted on said axis; a tube clamping member carried by said arm; and a mandrel located within the part of said tube within said tube clamping member.

11. A machine comprising a plate; means mounted thereon and adapted to carry a tube to be bent and to move the same endways; a guide roller; an axis; an arm mounted on said axis; a tube clamping member carried by said arm; an expanding mandrel located within the part of said tube

within said tube clamping member; and means whereby said expanding mandrel may be expanded.

12. A structure comprising a sole plate; means mounted thereon and adapted to carry a tube to be bent and to move the same endways; an adjustable guide roller; an axis; an arm mounted on said axis; a clamp bracket carried by said arm; jaws adapted to grip said tube and fitted to said clamp bracket; teeth or serrations on said jaws; and wedging means for securing said jaws to said clamp bracket.

13. A machine comprising a plate; means mounted thereon and adapted to carry a tube to be bent and to move the same endways; an adjustable guide roller; a carriage adapted to travel in a direction at right angles to the endways moving tube; a spindle carried by said carriage; an arm mounted on said spindle; a tube clamp carried by said arm; a frame; an adjustable carriage mounted on said frame; and rollers carried by said frame for guiding said tube as it is being bent.

14. A tube bending machine comprising a plate; means mounted thereon and adapted to carry a tube to be bent and to move the same endways; an adjustable guide roller; an axis; an arm mounted on said axis; a tube clamping member carried by said arm; and a guide roller adapted to move with the bent portion of the tube as the bend is being formed.

CARL ROBERT HUGO BONN.
